UNITED STATES PATENT OFFICE

1,987,641

COIN OPERATED VENDING MACHINE

Frank J. Rowse, Pawtucket, R. I.

Original application November 23, 1926, Serial No. 150,360. Divided and this application September 30, 1930, Serial No. 485,443

12 Claims. (Cl. 194—85)

This invention relates to improvements in coin-controlled vending machines as disclosed in my application, Serial No. 150,360, filed November 23, 1926, now Patent Number 1,782,768 from which the present application is divided. The present invention relates more particularly to the improved coin-operated mechanism and the package-delivering means operated therefrom as shown and described in the original application.

10 A principal object of the present invention is to provide a machine of the type specified having improved coin-operated mechanism of simple construction and proof against derangement or getting out of order.

15 Another object of the invention is to provide a machine of the type specified having means for preventing the insertion of the coins when the supply of articles is exhausted.

Another object of the invention is to provide a 20 machine wherein the delivery-mechanism for the articles to be vended acts positively after the insertion of the proper coin, but only when the coin has passed through the mechanism into the cash drawer or till.

25 Further objects of the improvement are set forth in the following specification which describes a preferred embodiment of the invention as illustrated by the accompanying drawings. In the drawings:

30 Fig. 1 is a front view of the improved vending machine showing its main casing partly broken away and illustrating the general arrangement of the coin-controlled operating mechanism in dotted lines;

35 Fig. 2 is a side view of the machine showing its casing in section on line 2—2 of Fig. 1;

Fig. 3 is an enlarged front view of the coin-controlled operating-mechanism of the machine;

40 Fig. 4 is an enlarged part-sectional side view of the coin-controlled operating-mechanism of the machine showing the front of the casing in section;

45 Fig. 5 is a detailed view of the means for connecting the operating-crank with the coin-controlled mechanism;

Fig. 6 is an enlarged detailed view of the coin-carrier and coin-ejecting mechanism showing the method of ejection of the coin;

50 Fig. 7 is an enlarged side view of the coin-controlled mechanism and delivery-mechanism, with the casing of the machine shown in section on line 7—7 of Fig. 1, and illustrating the parts in normal position prior to the insertion of the coin;

55 Fig. 8 is a front elevation of the same showing the parts in the same relation;

Fig. 9 is a view similar to Fig. 7 showing the coin-carrier in position after having been operated to actuate the delivery-mechanism and 60 after the coin has been ejected; and

Fig. 10 is a front view of the same with the parts in the same relation.

In its present embodiment the invention is illustrated as applied to a machine for vending hand-towels rolled or folded into small oblong packages containing a piece of soap, and for convenience of description the articles to be vended will hereinafter be referred to as packages; although it is to be understood that the machine may be adapted for vending any other kind of article or commodity.

The coin-controlled mechanism of the machine is of that type in which the coin is inserted through a slot in the front of the casing and received in a coin-carrier, so-called, where it becomes the active element for effecting the operation of the delivery- or vending-mechanism. That is to say, with the proper coin in position in the coin-carrier suitable means are operated manually to cause the coin to function to positively actuate the delivery-mechanism whereby, when the coin is finally ejected from the carrier into the cash-box, the delivery-mechanism will be again actuated to release the package to cause it to fall into position to be accessible for removal from the machine through an opening in the casing.

Referring first to Figs. 1 and 2 of the drawings, the improved machine comprises a main cabinet or casing 2 which contains the supply of articles to be vended and the coin-controlled delivery-mechanism. The box-like cabinet is clearly shown and described in the original application above referred to and therefore needs no detailed explanation. Suffice it to state that the articles to be vended are supported in a removable magazine or chute 56 located in the upper part of the casing 2 and are ejected rearwardly from the bottom of the chute by the delivery-mechanism to be deposited on the sloping bottom 17 whereby they slide down through an opening 33 onto a shelf or ledge 30 at the bottom of the casing. The front part of the casing 2 is cut away to provide for the insertion of a supplementary framework or casing 35 which carries the complete operating-mechanism of the machine embodied in a unitary structure.

The front wall 36 of the casing 35 is provided with a coin-slot 65, preferably inclined to the vertical as illustrated in Fig. 1. A main operating shaft 66 is journalled at its rearward end in the back-strip 49 of the casing 35 and projects forwardly through the front wall 36 of the casing. The shaft 66 is threaded to screw into the hub 67 of a crank-handle 70 which serves as the manual means for operating the coin-controlled mechanism of the machine. As shown in Fig. 5, the hub 67 carries a key 68 adapted to engage suitable slots in a ratchet-plate 71 carried by the shaft 66 at the rear of the front wall 36. The ratchet-plate 60

71 is connected with an opposite plate 72 by means of screws 73, see Figs. 3 and 4, passing through tubular hubs 74 which form the separating medium between the plates 71 and 72. Extending 5 between the plates 71 and 72 is an inclined coin-rest 75, these last-named parts forming the main elements of the coin-carrier, hereinafter designated in general by the reference character 76. It will thus be seen that the coin-carrier 76 is 10 mounted fast on the shaft 66 to be rocked about its axis by means of the crank 70. A spring 77 coiled around the shaft 66 bears with one end against the under side of the coin-rest 75 while its opposite end is held by a stud 78 projecting 15 from the rearward face of the front wall 36, see Figs. 3 and 4. The stud 78 projects through an arcuate slot 79 in the ratchet-plate 71 and serves as a stop to limit the movement of the coin-carrier 76 rotatively on its axis, the spring 77 tending to normally maintain the coin-carrier in the 20 position illustrated in Figs. 1 and 3 with the coin-rest 75 in line with the inclined coin-slot 65 to adapt it to receive the coin C, represented by dot-and-dash lines. It will be apparent also that the 25 spring 77 will act to return the coin-carrier to initial position after it has been rotated to its full extent.

It will be noted by reference to Fig. 3 of the drawings that the edge of the ratchet-plate 71 is 30 cut back at 80 and formed with a portion 81 of relatively short radius terminating in a series of ratchet-teeth 82. Opposite this edge of the ratchet-plate 71 is a pawl 69 pivoted on a stud 99 and operated by a spring 106 to engage its toe with 35 the teeth 82. The spring 106 is coiled around the stud 99 with one end bearing against an inclined portion 84 of the pawl 69 and its other end anchored to a lug 83 projecting rearwardly from the front-plate 36. As shown in Fig. 4, the pawl 69 is 40 of yoke-shape, having two arms pivoted on the stud 99 and connected by the inclined cross-piece 84. The pawl 69 is adapted to be tripped by a rockable arm 85 which is provided with a cam face 86 for engaging the toe of the pawl whereby 45 to release it from the teeth 82 and maintain it in position as shown in Fig. 3. The cam-arm 85 forms a part of the main operating element or presser-lever 100, to be later described, through 50 which the coin acts to energize the delivery-mechanism of the machine.

The coin-rest 75 is provided with means at its lower end for engaging the rim of the coin C to hold it in place thereon after it has slid down beyond the coin slot 65. At one side of the coin-rest 75 is a ledge or abutment 87 projecting from the rearward face of the ratchet-plate 71 with its lower edge extending parallel with and spaced above the face of the coin-rest, see Figs. 7 and 9. As shown more clearly in Fig. 6, the ledge 87 is 55 spaced away from the coin-rest 75 a sufficient distance to permit the coin to slide freely thereunder and also to allow the coin to tilt or rock, as indicated by the dash lines in Fig. 6, when it is ejected from the coin-carrier in a manner as later explained. On the opposite side of the coin-rest 60 is a pivoted lever 90 abutting the side of the plate 72. The lever 90 is formed with an abutment or overhanging beveled shoulder 89 inclined upwardly toward the top of the coin-plate as shown 65 most clearly in Figs. 3 and 8. The present construction of the coin-holding means provides an improvement over the similar instrumentalities in my prior United States Patents Nos. 992,258, May 16, 1911; and 1,568,770, January 5, 1926.

75 In the present construction the shouldered

abutment 89 is a part of the independently movable arm or lever 90 which is pivoted at 91 on one of the hubs 74 separating the two plates 71 and 72, see Fig. 8. The abutment 89, called for convenience the coin-holder, is held in operative relation with respect to the coin-rest 75 by means of a latch or detent 92 which engages a shoulder 93 cut into the edge of the lever 90. The latch 92 is of bifurcated construction in plan view, as shown more particularly in Fig. 9, and overlies the face of the coin-rest 75 in inclined relation thereto, whereby to provide a guard for guiding the coin into place beneath the coin-holder 89 and ledge 87, see Fig. 8, to insure that the coin will lie flat against the rest. The detent-latch 92 is provided with projecting pintles 94 on its opposite sides which are received in suitable holes in the plates 71 and 72 to pivotally mount the latch above the coin-rest 75. A spring 95 is coiled around one of the pintles 94 with one end bearing on the top of the latch and its opposite end anchored to the plate 72, see Figs. 8 and 9, thus tending to rock the latch to engage its finger 96 with the shoulder 93 in the edge of the lever 90. Extending in the opposite direction from the finger 96 on the latch 92 is a tail-piece 97 adapted to be engaged by a strip or plate 98 which projects at right-angles from the front wall 36 of the casing 35, see Fig. 10. Through this engagement the latch 92 is rocked to release its finger 96 from the shoulder 93 on the lever 90. The release of the detent-latch 92 allows the lever 90 to rock on its pivot 91 to release the coin-holder 89 from the edge of the coin, whereby the latter is ejected from the coin-carrier in the manner as later more fully explained.

As before indicated, the presser-lever 100 constitutes the means for energizing the delivery-mechanism of the machine, being moved by and with the coin-carrier through the action of the coin thereagainst. The presser-lever 100 is provided with a hub 101 which is free to rotate on the main operating shaft 66 so that the coin-carrier is movable independently thereof when 40 no coin is in place on the carrier. The presser-lever 100 has a curved finger 102 adapted to project through a longitudinal slot or opening 103 in the coin-rest 75. When a coin C is in place 45 on the coin-rest 75 and held by the coin-holder 89, the end of the finger 102 will bear against its under side so that the coin will act to rock the presser-lever under the movement of the coin-carrier 76. The rearwardly extending arm 85 of the presser-lever 100 is formed with a cam-face 86 which, as before indicated, is adapted 50 to slide under the toe of the pawl 69 to rock the latter to release it from the ratchet-teeth 82. At the end of its cam-face 86 the arm 85 is provided with a shoulder 105 which strikes 55 against the end of the pawl 69 to limit the return movement of the presser-lever 100 after it has been operated from the coin-carrier. The presser-lever 100 is connected to operate the delivery-mechanism of the machine through instru- 60 mentalities as next described.

Extending forwardly from the vertical plate 49 on the casing 35 are two arms 108 and 109, to which is pivoted a swinging delivery-frame or package-carrier 110. The frame 110 comprises 70 two upright arms 111 joined by a web 112, see Figs. 7 to 10, and having a tubular sleeve or bearing 113 extending horizontally at the bottom. Suitable studs 114 are screwed into the ends of the bearing or sleeve 113 with their heads jour- 75

nalled in holes in the arms 108 and 109, as clearly shown in Fig. 8. The frame or package-carrier 110 is thus adapted to rock on an axis at right-angles to the axis of the coin-carrier, being controlled by a helical spring 115 coiled around the sleeve 113. One end of the spring bears against the vertical plate 49 at the back of the casing 35 and its opposite end is bent around the web 112 of the frame 110 as shown at 116 in Fig. 7. The tension of the spring 115 thus tends to rock the upper part of the frame 110 towards the front of the casing 35, its movement in this direction being limited by the engagement of an arm 117 at its lower end with a detent lug 118 on the arm 109, see Fig. 7. The arm 117 is provided at its end with a hole into which is hooked the end of a link 119 which connects the frame or package-carrier 110 with the presser-lever 100, see Figs. 7, 9 and 10. It will thus be seen that the rocking movement of the presser-lever 100 in a contra-clockwise direction will cause the package-carrier 110 to be swung away from the front of the casing into the position shown in Fig. 9.

Pivoted between the upper ends of the arms 111 of the frame 110 is a shelf or rest 120, the rearward free end of which is supported on the upper edge of an offset portion 121 of the vertical plate 49, see Fig. 7. The rest or shelf 120 is thus sustained in position beneath the magazine 56 as shown in the view last referred to, but the packages are supported slightly above the shelf by means of rests or ledges 124, shown in Figs. 7 and 8 as projecting inwardly from the sides of the chute. The packages are slid off from the rests or ledges 124 by means of pusher-fingers 125 projecting rearwardly from the upper ends of the arms 111 of the frame 110. These pusher-fingers 125 are formed on slides 126 which are mounted to move up and down on the sides of the frame 110. As shown in Figs. 7 and 8, screws 127 which form the pivots for the sliding shelf 120 are screwed into hollow studs 128 having their ends set against the outer faces of the arms 111. The slides 126 have elongated slots 129 engaged by the body of the studs 128 whereby they may slide thereon; the lower ends of the slides 126 being guided by offset lugs 130 projecting through slots 131 at the bottom of the arms 111. The slides 126 are thus supported to move vertically on the arms 111 of the frame 110, being normally maintained in their uppermost position by the ends of a wire spring 132 which is coiled around a screw 133 secured in the web 112 of the frame and has extensions or legs 134 reaching outwardly through the slots 131 to bear against the lower ends of the slides as clearly shown in Figs. 7 and 8. Besides serving as pushers to slide the packages off from the ledges 124, the slides 126 also function to engage beneath the stack of packages remaining in the chute after one has been discharged therefrom, whereby to take the weight of the same during the return movement of the package-carrier to prevent undue friction or retardation of its action, all as more fully explained hereinafter.

The package-carrier or frame 110 is adapted to be engaged by a trip-lever or pawl 140 to prevent it from returning to normal position after the last package has been dropped into position to be delivered from the machine, see Figs. 9 and 10. The trip-lever 140 is pivoted on a stud 141 screwed into the plate 98, previously referred to as projecting rearwardly from the front of the casing 35, and is formed with a forwardly pro-

jecting curved finger 142 which is normally adapted to be engaged by the sides of the packages P as they slide down in the chute 56, see dotted lines in Fig. 9. Below the finger 142 the trip-lever 140 is formed with a detent-shoulder 143 which, when the lever is rocked forward into the position indicated by full lines in Fig. 9, will engage in back of the shelf 120 to prevent the package-carrier from completing its return movement toward the front of the casing. The trip-lever 140 is operated by gravity to cause it to tilt downwardly when the last package has been delivered from the chute 56, being held in this position by a toe 144 which strikes against the front wall 36 of the casing 35, see Fig. 9.

A coin receptacle or till 145, constructed as an inclined shelf, is pivoted between rearwardly-extending arms 44 on the casing 35. The till 145 is normally held in raised position to adapt it to receive the coins through its engagement with the bolt 152 of a lock 150, the arrangement of these parts being more fully explained in my prior application before referred to.

Having now described the construction and arrangement of the coin-operated mechanism and its associated delivery means, the method of operation of these devices will be next explained. The articles to be vended are placed in the chute or magazine 56 with the lowermost package resting on the ledges 124 projecting inwardly from its sides. The till 145 is raised and locked in place to receive the coins as they are ejected from the coin-carrier and the machine is thus made ready for operation.

Normally, with the machine loaded, the operating crank-handle 70 may be turned in a contra-clockwise direction within certain limits as defined by the stop-pin 78 engaging the end of the slot 79 in the ratchet-plate 71. Unless there is a coin in the coin-carrier, however, such movement of the crank 70 will fail to operate any part of the mechanism, it being necessary that a coin be in position in the carrier to serve as the active element for actuating the presser-lever 100. To operate the machine to vend a package or other article the coin C is inserted through the coin-slot 65, whereupon it will slide down on the coin-rest 75 to lodge its rim beneath the ledge 87 and coin-holder 89. The operator then turns the crank 70 to rotate the coin-carrier 76 on its axis whereby the coin C will impinge against the end of the finger 102 of the presser-lever 100 to rock the latter with the carrier. The movement of the presser-lever 100 is communicated through its link 119 to the delivery-frame or package-carrier 110 to rock the latter toward the rear of the casing.

As the package-carrier 110 is rocked in this direction the pusher-fingers 125 on the slides 126 will come against the lowermost package P in the chute 56, see Fig. 7, and as the movement of the carrier is continued will slide this package out from under the stack in the chute. As the frame of the package-carrier 110 swings rearwardly the shelf or rest 120 carried thereby is slid out to receive the package P pushed out from under the stack in the manner as clearly illustrated in Fig. 9. This view illustrates the crank-handle 70 at the limit of its stroke, at which point the coin-carrier 76 has been rocked to the position shown in Fig. 10, the package-carrier 110 being then at the end of its throw with the package completely ejected from the chute 56 and resting on the shelf 120, see Fig. 9. As the coin-carrier is rocked or rotated in this

manner the pawl 69 rides across the ratchet-teeth 82, see Fig. 3, engaging successively therewith to prevent retrogressive movement of the carrier; it being noted that the pawl is released from the high point of the cam 86 on the presser-lever 100 immediately said lever is rocked with the coin-carrier. It will be apparent, therefore, that the package-carrier is prevented from swinging back after its presser-fingers have once engaged with a package P so that it cannot partly eject a package and then return to first position. That is to say, if the pressure on the crank-handle 70 is released through accident or mistake it will not prevent the proper functioning of the delivery-mechanism, the operator being only required to continue the movement of the crank-handle to its full extent to effect the delivery of the package. As the coin-carrier 76 is rocked to its full extent the tail-piece 97 of the detent-latch 92 is brought into engagement with the side of the plate 98 as shown in Fig. 10. That is to say, at the last end of the stroke of the coin-carrier the tail 97 of the latch-lever 92 strikes against the plate 98 to release the toe of said latch from the notch or shoulder 93 in the lever 90 carrying the coin-holder 89. Immediately the detent-latch is released the pressure of the presser-lever 100 on the under side of the coin C will cause the latter to raise the coin-holder 89 away from the coin-rest 75 as indicated by the dotted lines in Fig. 6. The lifting of the coin-holder 89 will thus release one edge of the coin C to allow it to rock or cant away from the coin-rest 75 under the pressure of the lever 100, whereby it will slide freely out from under the ledge 87 and drop down into the till 145 as indicated by the dot-and-dash lines in Fig. 10. In this way the coin is positively ejected from the operating mechanism without chance of its binding or sticking in the coin-carrier. After the coin has been discharged from the coin-carrier 76 the lever 90 returns the coin-holder 89 to normal position under the action of the spring 95 and as the detent-latch 92 is released from engagement with the plate 98 upon the return of the coin-carrier 76, the latch will again lock the coin-holder in operative relation with respect to the coin-rest 75.

Immediately the presser-lever 100 is released by the discharge of the coin C from the coin-carrier 76 the spring 115 acts on the package-carrier 110 to swing the latter back to first position as illustrated in Fig. 7. This movement of the carrier 110 rocks the presser-lever 100 on its axis to return it to first position as shown in Fig. 8 with its shoulder 105 engaging against the end of the pawl 69 to prevent further movement thereof. The return movement of the lever 100 also acts through the engagement of its cam-face 86 with the toe of the pawl 69 to release the latter from the ratchet-teeth 82, see Fig. 3, whereby, when the crank-handle 70 is released, the coin-carrier 76 will be returned to first position under the action of its spring 77. In this way the parts of the mechanism are returned to normal relationship to adapt them to function again in the same manner when another coin is inserted through the slot in the front of the machine.

It has been stated that the package-carrier 110 is returned to first position after the ejection of the coin from the coin-carrier 76, and during this return movement of the carrier its shelf 120 is withdrawn from under the package P resting thereon so that the latter will drop down, as

indicated by the dash lines in Fig. 9, to slide forwardly on the sloping bottom of the casing 2. As the package P delivers through the opening 33 in the front of the casing its forward edge meets the lip 32 of the shelf 30 to prevent it from sliding off while also raising it into position as indicated in the dash lines in Fig. 2 to adapt it to be conveniently grasped in the fingers. 5

As the package-carrier 110 swings back to the position shown in Fig. 7 the arcuate upper edges 10 of the slides 126 slide in under the under side of the lowermost package in the chute 56 to sustain the whole stack of packages above the rests or ledges 124; that is to say, the weight 15 of the stack of packages is supported on the slides 126 by the resilient pressure of the spring 132 acting against the lower ends of the slides. In this way the cumulative weight of the packages is prevented from exerting any considerable pressure to resist the return movement of the package-carrier so that there is no chance of the latter becoming stuck or impeded in its action. As the carrier reaches its first position, shown in Fig. 7, the slides 126 slide out from 20 under the lowermost package P which thereupon drops down into place on the rests or ledges 124 at the sides of the chute 56. 25

It has been explained that after a coin has been inserted in the machine and the crank-handle 70 partly rotated to operate the coin-carrier 30 76, return movement of the carrier is prevented by the engagement of the pawl 69 with the ratchet-teeth 82. The coin-carrier 76 is thus locked in position with its front-plate 71 closing the coin-slot 65 in the manner of a shutter to 35 prevent the reception of another coin until the delivery-mechanism of the machine has functioned to deliver a package and the first coin has been cleared from the mechanism. This provision guards against the clogging of the mechanism by the insertion of a second coin when one is already in place on the coin-carrier and prevents the loss of a coin by the operator. The same means also acts in the manner as next explained to prevent the insertion of a coin in the 40 machine when the supply of articles is exhausted. 45

For this latter purpose the trip-lever 140 is caused to rock forward into the position shown by full lines in Fig. 9 when the last package has been slid out from the bottom of the chute 56. After 50 this last package has been delivered from the shelf 120 the return movement of the package-carrier 110 is arrested with the carrier in position as indicated in fragmentary view by the dash lines in Fig. 9 through the engagement 55 of the detent-shoulder 143 on the lever 140 against the forward edge of the shelf 120. This detention of the frame or carrier 110 holds the presser-lever 100 from being returned to first position so that the pawl 69 remains engaged with the last tooth 60 82 on the ratchet-plate 71 to prevent the coin-carrier from being returned to first position. The coin-slot 65 is therefore maintained closed to prevent the insertion of a coin when the machine is empty. When a fresh supply of packages is placed in the chute 56 the trip-lever 140 is returned to normal position bearing against the sides of the lowermost packages, so that as long as a supply of articles remains in the chute the package-carrier 110 is free to swing back upon the release of the presser-lever 100 at each ejection of a coin. 65

It will be observed that my invention provides a particularly simple, compact and efficient mechanism for the purpose explained. Both the pack- 70 75

age-delivery mechanism and the coin-ejecting devices are positive in action and proof against derangement or getting out of order.

As before noted the coin-operated mechanism

5 is also practically proof against derangement or getting out of order and is designed to operate to protect the purchaser as well as the vender.

While I have herein shown and described a preferred form of construction of the improved device 10 it is obvious that various modifications may be made in the form and arrangement of its parts without departing from the spirit or scope of the invention. Therefore, without limiting myself in this respect, I claim:

15 1. In a coin-operated mechanism, the combination of a manually-rotatable coin-carrier, a coin-rest on the coin-carrier provided with an opening, a ratchet rotatable with the coin-carrier, a pawl adapted to engage the ratchet to check retrogressive movement of the coin-carrier, and 20 a presser-lever movable independently of the coin-carrier and having a portion projecting through the opening in the coin-rest to be engaged by the coin to cause the lever to be moved with the coin-carrier, said lever provided with means for disengaging the pawl from the ratchet on the coin-carrier when the coin is discharged from the carrier whereby to allow the coin-carrier to be returned to first position.

25 2. In a coin-operated mechanism, the combination of a manually-rotatable coin-carrier having a rest for the coin, a ratchet rotatable with the coin-carrier, a pawl for engaging the ratchet to prevent retrogressive movement of the coin-carrier, a lever movable independently of the coin-carrier and adapted to be engaged by the coin to be moved by and with the carrier, said lever formed with a cam for releasing the pawl from the ratchet, means for returning the lever to first position upon the discharge of the coin from the coin-carrier to effect release of the pawl, and means for returning the coin-carrier to first position after the lever has released the pawl.

30 3. In a coin-operated mechanism, the combination of a rotatable coin-carrier comprising a ratchet and a coin-rest, a pawl for engaging the ratchet to prevent retrogressive movement of the coin-carrier, a presser-lever rotatable coaxially of the carrier and having a portion adapted to be engaged by the coin when the latter is in place on the rest to cause the lever to be moved by and with the carrier, said lever formed with a cam-face for engaging the toe of the pawl to release it from the ratchet, delivery-mechanism operated from the presser-lever, a spring for operating the presser-lever to release the pawl when the coin is discharged from the coin-carrier, and a spring for returning the coin-carrier to first position after the lever has released the pawl from the ratchet.

35 4. In a coin-operated mechanism, the combination of a plate having a slot for the insertion of a coin, a coin-carrier rotatable at the rear of said plate, a coin-rest on the carrier adapted to align with the slot in the plate, a spring for rotating the coin-carrier to align the coin-rest with the slot, a ratchet rotatable with the coin-carrier, a pawl for engaging said ratchet to prevent retrogressive movement of the carrier under the action of its spring, a presser-lever adapted to be engaged by a coin held on the coin-rest to be moved by and with the coin-carrier, said lever adapted to normally engage the pawl to maintain it out of engagement with the ratchet and to release the pawl when the lever is returned to

first position after the discharge of the coin from the carrier, and means to return the presser-lever to first position after its release by the discharge of the coin.

5 5. In a coin-operated mechanism, the combination of a rotatable shaft, a coin-carrier rotatable with said shaft and comprising opposite plates with one of said plates formed with a ratchet, a coin-rest extending between the plates and provided with an opening, means for holding the coin flat against the rest and across the opening, a pawl engaging the ratchet to prevent retrogressive movement of the coin-carrier, a presser-lever pivoted on the shaft and provided with a finger adapted to project through the opening in the coin-rest to be engaged by the coin, said lever having means engaging the pawl to hold it from engagement with the ratchet on the coin-carrier and adapted to release the pawl when the lever is returned to first position, a spring for returning the coin-carrier to first position, a spring for returning the presser-lever to first position to engage the pawl, and means for releasing the coin from the coin-rest at the end of the movement of the coin-carrier whereby the presser-lever will be returned to first position to release the pawl to allow the return of the carrier to first position.

10 6. In a coin-operated mechanism, the combination of a rotatable coin-carrier having a coin-rest, means on the carrier for holding the coin against the rest, means for locking the coin-holding means against the coin, and means for releasing the locking-means as the coin-carrier reaches the end of its movement.

15 7. In a coin-operated mechanism, the combination of a coin-carrier having a coin-rest, means on the carrier for holding the coin against the rest and adapted to be released to discharge the coin, detent-means for maintaining the coin-holding means in engagement with the coin, and means operative at the end of the movement of the coin-carrier to release the detent-means to disengage the coin-holding means from the coin to allow it to be ejected from the carrier.

20 8. In a coin-operated mechanism, the combination of a coin-carrier having a coin-rest, a movable coin-holder for engaging the coin to hold it flat against the rest, a detent-lever engaging the coin-holder to lock the latter in engagement with the coin, and means for rocking the detent-lever to release the coin-holder when the coin-carrier reaches the end of its movement.

25 9. In a coin-operated mechanism, the combination of a rotatable coin-carrier having a coin-rest, a fixed ledge at the side of the coin-rest adapted to engage the edge of the coin, a movable coin-holder for engaging the opposite edge of the coin to hold it flat against the rest, detent-means for locking the coin-holder in fixed relation with respect to the rest, and means operated at the end of the movement of the coin-carrier to release the detent-means to cause the coin-holder to release the coin.

30 10. In a coin-operated mechanism, the combination of a rotatable coin-carrier having opposite plates with a coin-rest extending therebetween, a fixed ledge on one of the plates for engaging the edge of the coin, a coin-holder pivoted to the opposite plate and having an inclined beveled shoulder for engaging the opposite edge of the coin, detent-means for locking the coin-holder in fixed relation with respect to the coin-rest, and means to release the detent-means to allow the coin-holder to move to release the coin.

11. In a coin-operated mechanism, the combination of a rotatable coin-carrier having a coin-rest with an opening therein, a presser-lever movable independently of the coin-carrier and provided with a portion projecting through the opening in the coin-rest to adapt it to be engaged by the coin to cause it to be moved by and with the coin-carrier, a coin-holder on the carrier adapted to be set in position to hold the coin flat against the coin-rest, a detent for locking the coin-holder in engagement with the coin, and means to release the detent when the carrier reaches the end of its movement whereby the coin-holder will be released from the coin to cause the ejection of the latter from the coin-carrier under the pressure of the presser-lever.

12. In a coin-operated mechanism, the combination of a rotatable coin-carrier having a coin-rest, a fixed ledge on the coin-carrier for engaging the edge of the coin, a lever pivoted to the coin-carrier and having means for engaging the opposite edge of the coin, a pivoted detent-latch for engaging the coin-holding lever to lock the latter in engagement with the coin, a presser-lever pivoted on the axis of the coin-carrier and adapted to be engaged by the coin when the latter is placed on the rest, and means for operating the latch to release the coin-holding lever whereby the coin will be discharged from the carrier under the pressure of the presser-lever.
